United States Patent Office.

W. STINSON LORD, OF CRAWFORD, MISSISSIPPI.

Letters Patent No. 100,166, dated February 22, 1870.

IMPROVED PUNCH AND PRESS.

The Schedule referred to in these Letters Patent and making part of the same.

To all whom it may concern:

Be it known that I, W. STINSON LORD, of Crawford, in the county of Lowndes, and State of Mississippi, have invented a new and Improved Punch and Press; and do hereby declare that the following is a full, clear, and exact description thereof, reference being had to the annexed drawing.

Figure 1 is a perspective view of the press or punch.

Figure 2 is an end view.

Figure 3 represents the moving head.

Figure 4 represents the stem or piston of punch.

A A are the sides or frame of punch, and are made of iron of such proportions to be of sufficient strength, and are the required distance apart to allow the moving head to work between them. The sides A A have three slots in each, as at a, b, and c.

a and c are circular or eccentric to the slot b.

b is a vertical slot.

B B represent the moving head, with holes d, e, and f, through which pins i, k, and n pass.

4 is a lever fastened to head B.

D D is the piston or stem of punch.

The part H works in space C in head B, and pin k passes through hole h in stem D.

m is a guide fastened to and between the sides A A, and stem D passes through a hole in m, which keeps stem D firmly in its place.

The pins i, k, and n can have friction-rollers on each end and slots a, b, and c will be of required size to receive them. The pin n will not pass through space C, but will be made in two parts, and each part screwed into sides of head B, thus giving free action to stem D, and obviate the cutting of stem D as at S.

By raising lever 4 the pin i will be carried to 1 and n to 3, which will raise pin k to 2. The stem D being carried with pin k, will raise the punch to its full height. The lever 4 being pressed downward, will bring pins i and n down in eccentric slots a and c, thereby causing pin k to descend in slot b, and forcing stem D down with the combined power of lever 4 and eccentric or wedge-shaped slots a and c.

What I claim as new, and desire to secure by Letters Patent, is—

The combination of the frame A, having the slots a b c, the perforated and slotted head B, the lever L, and the notched stem or punch-stock D; substantially as and for the purpose set forth.

In testimony that I claim the foregoing improvement in punch and press, I have hereunto set my hand this 10th day of September, 1869.

W. STINSON LORD.
